UNITED STATES PATENT OFFICE.

ALGIE WIBBELS, OF WOLBACH, NEBRASKA.

RESTRAINING DEVICE.

Application filed October 14, 1924. Serial No. 743,582.

To all whom it may concern:

Be it known that I, ALGIE WIBBELS, a citizen of the United States, residing at Wolbach, in the county of Greeley and State 5 of Nebraska, have invented certain new and useful Improvements in Restraining Devices, of which the following is a specification, reference being had to the accompanying drawings.

10 This invention relates to certain improvements in restraining devices and has relation more particularly to a device of this general character especially designed and adapted for use to hold hogs, and it is an object of 15 the invention to provide a novel and improved device of this general character in which the hog is adapted to be positioned together with holding members adapted to engage the animal from opposite sides and 20 particularly at points just behind the ears.

The invention consists in the details of construction and in the combination and arrangement of the several parts of my improved restraining device whereby certain 25 important advantages are attained and the device rendered simpler, less expensive and otherwise more convenient and advantageous for use, as will be hereinafter more fully set forth.

30 The novel features of my invention will hereinafter be definitely claimed.

In order that my invention may be the better understood, I will now proceed to describe the same with reference to the accompanying drawings, wherein:

Figure 1 is a view in front elevation illustrating a restraining device constructed in accordance with an embodiment of my invention, a second position of certain of the 40 parts being indicated by broken lines;

Figure 2 is a view in top plan of the structure as illustrated in Figure 1;

Figure 3 is a view in side elevation of the device as herein disclosed;

45 Figure 4 is a fragmentary sectional view illustrating certain details of construction as herein disclosed;

Figure 5 is a fragmentary view in perspective of a rear portion of the device as 50 herein set forth;

Figure 6 is a fragmentary view in perspective illustrating in detail the mounting of the guide bars or members.

As herein disclosed, my improved restraining device comprises the end sills 1 preferably angle irons and with their hori-

zontal flanges *a* inwardly directed. Interposed between the sill 1 and resting upon the horizontal flanges *a* is the bottom plate or wall 2, said plate having its extremities 60 riveted, as at 3, or otherwise secured to said flanges *a*. The sills 1 extend beyond opposite sides of the bottom plate or wall 2 and secured to the end portions of the vertical flange *b* of the front sill 1 are the upstanding and diverging posts 4 also herein disclosed as comprising angle irons. The inwardly directed flange *c* of each of the posts 4 has its lower portion outwardly disposed to provide a brace member 5, the free 65 extremity of which, resting upon and secured as at 6, to the inwardly directed flange *a* of said front sill 1.

The rear sill 1 at opposite sides of the bottom plate or wall 2 has also secured thereto the upwardly disposed and diverging posts 7 each of which also comprising an angle iron and having its outer flange *d* extended to overlie the vertical flange *e* of said rear sill and secured thereto, as at 8. 70 Associated with each of the posts 7 and the adjacent outer end portion of the rear sill 1 is a brace member or iron 9.

Secured to the posts 4 and 7 at each side of the bottom plate or wall 2 is a side wall 85 or plate 10 whereby a trough like body is provided to receive the hog.

The upper extremities of the posts 4 are connected by an elongated bar or member 11, the extremities of which as herein disclosed underlying the inwardly directed flanges *c* of the posts 4. Positioned in advance of the posts 4 and in parallelism therewith is a second member or bar 12 the extremities of which having interposed 95 therebetween and the flanges *c* the spacing blocks 14, each holding bolt 15 or the like being common to the adjacent extremities of the members or bars 11 and 12, the spacing block 14 and a flange *c*. The central 100 portions of the members or bars 11 and 12 also have interposed therebetween an additional spacing block 16 maintained in applied position by the holding bolts 17 or the like.

Pivottally connected, as at 18, to the front sill 1 at spaced points between the front posts 4 are the upstanding elongated arms 19 the upper extremities of which extending between the spaced parallel members or bars 11 and 12 and at opposite sides of the interposed central spacing block 16. The 110

lower or pivoted end portion 19^a of each of the arms 19 is squared and the pivoted end contacts with the horizontally disposed part or foot *x* having substantially an 5 L-shaped spring 20, the free extremity of the part or foot *x* being anchored to the front sill 1 at a desired point inwardly of the arm 19, while the stem *y* of the spring 20 extends upwardly of the arm 19 along 10 the outer edge thereof with the upper end portion of said stem *y* anchored, as at 21, to the arm 19.

The springs 20 operate to urge said arms 19 outwardly or one away from the other 15 and to normally maintain the same at the limit of their outward movement. The inward movement of the arms 19 is limited by contact of the pivoted ends of the arms 19 with the parts or feet *x* of the springs 20.

20 The upper end portion of each of the arms 19 is provided with a pair of outwardly and laterally directed arms 22 between which is pivotally supported a sheave 23. Disposed around the sheaves 23 is the 25 intermediate portion of a flexible member or cable C, said cable being disposed in opposite directions from the sheaves 23 providing portions or stretches 24 in crossed relation. Each of these portions or stretches 24 extends over the upper portion of a side plate or wall 10 and downwardly over an outwardly disposed sheave 26 carried by said wall. Said end portion or stretch of the cable is then extended 30 downwardly and over and under a second sheave 27 extending outwardly from said wall 10 but slightly spaced therefrom. Said portion of the cable then extends inwardly through an opening 28 in the wall 40 10 and over a pulley 29 extending within said opening and from which said portion of the cable is rearwardly directed so that it may be readily grasped to impose requisite pull thereon when it is desired to move the arms 19 inwardly one with respect to the other.

In practice, the hog is placed in the trough upon its back with its head extend-

ing beyond the front end of the trough so that upon requisite pull upon the end portions of the cable C the arms 19 may be caused to engage the animal from opposite 50 sides and preferably at a point inwardly of but immediately adjacent to the ears. It is to be understood, however, that I do not wish to be limited as to the exact manner in which the animal is to be placed within the 55 trough.

As particularly illustrated in Figure 5, the upper portion of a post 7 is provided with a fastening member 25 to which is adapted to be engaged the free end portion 60 of the cable C to hold or maintain the arms 19 in proper contact with the animal.

From the foregoing description it is thought to be obvious that a restraining device constructed in accordance with my invention is particularly well adapted for use by reason of the convenience and facility with which it may be assembled and operated, and it will also be obvious that my invention is susceptible of some change and 70 modification without departing from the principles and spirit thereof and for this reason I do not wish to be understood as limiting myself to the precise arrangement and formation of the several parts herein 75 shown in carrying out my invention in practice except as hereinafter claimed.

I claim:—

A restraining device of the class described comprising a trough open at its opposite ends and top, a pair of upstanding holding arms pivotally supported by the bottom of the trough at one end thereof, springs carried by the pivoted end portions of the arms for moving said arms in a direction one away from the other, said springs having inwardly disposed extensions coacting one with the other to limit the inward movement of the arms, and means for moving said arms inwardly one with respect to the other.

In testimony whereof I hereunto affix my signature.

ALGIE WIBBELS.
